DESIGN FOR A SUIT

Sidney Cohen, New York, N. Y., assignor to Morris
W. Haft & Bros., Inc., New York, N. Y.

Application October 30, 1947, Serial No. 142,213

Term of patent 3½ years

(Cl. D3—4(5.1))

To all whom it may concern:

Be it known that I, Sidney Cohen, a citizen of the United States of America, residing in New York city, county of New York, and State of New York, have invented a new, original, and ornamental Design for a Suit, of which the following is a specification, reference being had to the accompanying drawing, forming part thereof, wherein

I claim:

The ornamental design for a suit, substantially as shown.

SIDNEY COHEN.
